UNITED STATES PATENT OFFICE.

SAMUEL D. NESMITH, OF LA JOLLA, CALIFORNIA.

ELECTRIC WATER-HEATER.

1,224,117.

Specification of Letters Patent. Patented Apr. 24, 1917.

Application filed November 8, 1916. Serial No. 130,156.

To all whom it may concern:

Be it known that I, SAMUEL D. NESMITH, a citizen of the United States, residing at La Jolla, in the county of San Diego and State of California, have invented new and useful Improvements in Electric Water-Heaters, of which the following is a specification.

My invention relates to that class of water heating apparatus in which a current of electricity passing through a suitable resistant medium acts to raise the temperature of the water.

My invention consists in the employment of a suitable insulating material through which a series of narrow flat channels extend, and within which insulating material, multiple-connected conductors are embedded in such relation to the water conducting channels that the heat produced by the resistance of the conducting wires will be transmitted successively to the channels to which the wires are contiguous, so as to gradually raise the temperature of the water to the required degree.

It also comprises details of construction which will be more fully explained by reference to the accompanying drawings, in which—

30 Figure 1 is a sectional elevation through line 1—1 of Fig. 3.

Fig. 2 is a section through the line 2—2 of Fig. 1.

Fig. 3 is a section through the line 3—3 of Fig. 1.

Fig. 4 is a diagrammatic view of the arrangement of the conducting wires in multiplicity.

It is one of the objects of my invention to obtain a larger percentage of the heat units of the resistance material transmitted to the water channels, so as to reduce the amount of current consumed to the smallest degree, and to raise the temperature of the water by successive steps as it passes through the succeeding channels.

In the accompanying drawings, A represents a casing of any suitable material, and 2 is an inclosed body of insulating material having a series of thin, flat channels 3 made through it at intervals. Above and below the insulating material the exterior casing A is divided by suitable partitions 4, so as to form chambers 5, each of which connects alternately at the top and bottom with one or more of the water-containing channels.

6 is an inlet through which water is admitted from any suitable or desired source, passing into the first of the chambers 5, thence through the conducting channel 3 60 up to the similar chamber 5, at the opposite end, and thence passing down through a channel 3, which connects with the same chamber, thus passing alternately from top to bottom, as shown, and advancing through 65 the different channels to the exit or discharge passage 7.

8 are electrical conductors to which a current of electricity passes and from which the current is successively directed in multiple through conductors 9 which are embedded in the insulating material and at such a distance from the water-conducting channels that heat will be transmitted through the material to raise the temperature of the water, while the conductors themselves are thoroughly insulated from each other with no chance for a short circuit.

75 The operation will then be as follows: The water being admitted to flow through 80 the apparatus at any desired rate of speed, the current of electricity provided from any suitable source will pass through the insulated coils and will transmit its heat to the latter. Thus the heat transmitted from the first coil will raise the temperature of the water to a certain degree and the water passing from this channel through the channel 5 will enter the second channel 3 where it is again subjected to the action of the 85 electrical current from the conductors which are contiguous to this channel and the temperature is increased. It then enters the next chamber 5 and passes therefrom to the following channel 3, where it is again subjected to the heat of the contiguous conductors, and so on until the temperature is 90 gradually raised to the desired degree.

95 In this manner I economize the electrical current by causing it to act successively upon the water in the various channels and the amount of current consumed for the service rendered will be reduced to the smallest degree.

100 By this construction of heater the wires 105 are thoroughly embedded in the insulating material 2 and so are protected against contact at any point with the water traversing the channels.

110 This invention is especially and particularly useful for the rapid heating of water which is in circulation.

Having thus described my invention, what I claim and desire to secure by Letters Patent is—

- 5 1. An electric water heater including a casing having a top and a bottom one of which is removable, said top and bottom each having integral inwardly extending partitions, a body of insulating material having a series of flat water passages molded therein, and electrical wires embedded in said body adjacent the sides of said water passages, said body being insertible as a unit in said casing and engaged at its top and bottom with the free ends of the partitions so as to be supported by the partitions of the bottom.
- 10 2. An electric water heater including a casing having an inlet and an outlet, a body of insulating material having flat water channels molded therein and extending therethrough to cause the water to directly contact with said material, means to direct the water successively through the channels, and electrical wires embedded in said body.
- 15 3. An electric water heater including a casing, a body of insulating material in the casing, said body being molded with a series of narrow spaced flat water passages which latter extend through the top and bottom of the body, means to successively direct the water through said passages, and electrical wires embedded in said body and arranged in layers so as to present two sides disposed adjacent and between a pair of the passages.
- 20 4. An electric water heater including a casing having an inlet and an outlet, a body of insulating material having flat water

channels molded therein and extending therethrough to cause the water to directly contact with said material, the top and bottom of the casing having inwardly extending partitions the inner ends of which abut the top and bottom sides respectively of said body at points between the channels of the latter, said partitions being arranged to direct the water successively through said channels, and electrical wires embedded in said body.

40 5. An electric water heater including a casing having an inlet and an outlet, a body of insulating material having flat water channels molded therein and extending therethrough to cause the water to directly contact with said material, said body having its ends spaced from the adjacent walls of the casing so as to form water channels in conjunction therewith, said inlet and outlet registering with the last named channels respectively, said casing having inwardly extending partitions the inner ends of which abut the top and bottom sides respectively of said body at points between the channels of the latter, said partitions being arranged to direct the water successively through said channels, and electrical wires molded in said body.

50 In testimony whereof I have hereunto set my hand in the presence of two subscribing witnesses.

SAMUEL D. NESMITH.
